UNITED STATES PATENT OFFICE.

ELMER R. RAMSEY, OF DENVER, AND ALFRED L. BLOMFIELD, OF COLORADO SPRINGS, COLORADO, ASSIGNORS TO THE DORR COMPANY, OF NEW YORK, N. Y., A CORPORATION OF DELAWARE.

AUTOMATIC FEED CONTROL.

1,413,935.

Specification of Letters Patent. Patented Apr. 25, 1922.

Application filed April 5, 1919. Serial No. 287,906.

To all whom it may concern:

Be it known that we, ELMER R. RAMSEY and ALFRED L. BLOMFIELD, citizens of the United States, residing, respectively, at Denver, in the county of Denver and State of Colorado, and at Colorado Springs, in the county of El Paso and State of Colorado, have invented certain new and useful Improvements in Automatic Feed Controls, of which the following is a specification.

This invention relates to a method of automatically regulating the feed to classifiers, and its principal object is to provide a system of cooperative devices which operates to regulate the feed to a classifier by and proportionate to variations in the weight of all or part of the material under treatment.

Variations in the weight of a load of a separating apparatus of the type to which the invention is applicable, are directly proportionate to increases or decreases in the quantity of the coarser part or oversize of the material which in wet classification settles out of the liquid and suspended slimes, and it is specifically by variations in the weight of the coarse or oversize product of the classifier that the feed is regulated in the operation of our invention.

Another object of the invention is to utilize variations in the weight of an oversize product of the classifier for maintaining the load uniformly at a predetermined density by automatically increasing or decreasing a water supply in ratio to density variations.

The weight of the coarse product of the separating action is effective for the purpose of regulating the feed, while it is a part of the load of the classifier or after it is discharged therefrom, and we desire it understood that either method may be utilized within the principle of our invention.

A system of devices applicable for use under each of the above-named conditions has been shown in the accompanying drawings in which—

Figure 1, the system as employed when the feeding action and liquid supply are controlled by the material in the classifier, and

Figure 2, the system as arranged when variations in the weight of the oversize after it is discharged from the classifier is uti-

lized to regulate the feed of fresh material and the supply of additional liquid to the material under treatment.

Figure 3 represents a section of the valve which controls the water supply, in its normal, partially open position.

Referring to the drawings, the reference numeral 2 designates a classifier of suitable construction which receives its load from an endless belt 3 through the medium of a chute 4 and which discharges the oversize of the classified material through a chute 5.

The endless feed belt is mounted on rollers 6 and 7 and receives its load from a superposed bin 8, and the roller 7 is connected by a belt 18 with the rotary element of an electric motor 19 which receives its current from a source of electricity 20 through a circuit composed of conductors 21 and 22.

A rheostat 23 introducing a variable resistance in the circuit of the motor, is controlled by a contact on the long arm of the lever 12 so that when by variation of the weight of the material carried on the feed belt, the lever is moved about its fulcrum, the velocity of the motor will be proportionately reduced or increased.

In the operation of the above-described system the feed belt conveys the material discharged from the supply bin 8, continuously to the chute 4 which delivers it into the classifier and the valve 16, which preferably is of the butterfly type, is in a partially open position as shown in Figure 4 to continuously supply a certain quantity of water to the material under treatment.

When the load on the feed belt increases in weight so as to overbalance the resistance to the movement of the lever 12, consequent increase of density of the load in the classifier is obviated by an immediate increase of the liquid flowing to the classifier through the conduit 17, by further opening the valve through the medium of the connecting rod 15.

The movement of the lever at the same time increases the resistance to the current flow through the circuit, in the rheostat, whereby the movement of the feed belt is retarded until the conditions are again normal.

It will be seen that by these means, overloading of the classifier is automatically

avoided and that in case the supply of material to the feed belt is diminished so as to underload the classifier, the feeding action of the belt is automatically accelerated 5 by a movement of the lever in the opposite direction and a consequent decrease in the resistance to the current flow through the circuit in the rheostat, while at the same time the water supplied to the classifier is 10 diminished by a closing movement of the valve.

In the form of our invention shown in Figure 1 the classifier is pivotally supported at one of its ends as at 24, and it is at its 15 opposite end supported upon the short arm of a lever 25 whose opposite arm is by means of a link 26 connected with the short arm of a second lever 12.

A spring 14 acting upon the long arm 20 of the lever 12 compensates for the weight of the parts connected to its opposite arm and the link 15 connects the long arm of the lever with the crank arm 16 of a valve 16 which controls the flow of a liquid 25 through a conduit 17 leading from a source of supply and emptying into the classifier.

A rheostat 23 introducing a variable resistance in the circuit of the motor is controlled by a contact on the long arm of the 30 lever so that any movement of the lever about its fulcrum will change the velocity of the motor and in consequence that of the feed belt 3.

In the operation of the above-described 35 system the feed belt conveys the material discharged from the supply-bin 8, continuously to the chute 4 which delivers it into the classifier and the valve 16 which preferably is of the butterfly type, is in a partially open position as shown in Figure 3 to continuously supply a certain quantity 40 of water to the material under treatment.

When the load in the classifier increases 45 in weight so as to overbalance the resistance to the movement of the lever 12, consequent increase of density of the load is obviated by an immediate increase of the liquid flowing to the classifier through the conduit 17, by further opening the valve through the 50 medium of the connecting rod 15.

The movement of the lever at the same time increases the resistance to the current flow through the circuit, in the rheostat, whereby the movement of the feed-belt is 55 retarded until the conditions are again normal.

It will be seen that by these means, overloading of the classifier is automatically avoided and that in case the supply of material to the feed belt is diminished so as to underload the classifier, the feeding action of the belt is automatically accelerated by a movement of the lever in the opposite direction and a consequent decrease in the resistance to the current flow through the 60 65 sistance to the current flow through the

circuit in the rheostat, while at the same time the water supplied to the classifier is diminished by a closing movement of the valve.

In the construction illustrated in Figure 70 2, the feeding action of the belt is controlled by variations in the weight of the oversized product of classification after this discharge from the classifier in a determinate period of operation.

75 The oversize discharge from the classifier is through the chute 5 delivered onto an endless belt 27 which is mounted on rollers 28 and 29. One of the rollers is supported in stationary bearings 30 and the other is mounted in boxes 31 which are suspended by a link 32 from the short arm of the lever 12.

When the weight of the oversize discharge from the classifier in a determinate period of operation varies from a predetermined uniform quantity, the consequent pivotal movement of the belt 27 will cause an increase or decrease of the resistance to the current flow in the rheostat and a consequent retardation or acceleration of the 90 movement of the feed belt, while the supply of water to the material under treatment through the conduit 17 is proportionately reduced or augmented to regulate the density of the load in the classifier and 95 thereby assist in maintaining its operation at the maximum of efficiency.

It will thus be seen that by the use of our invention variations in the weight of the material under treatment in the classifier 100 directly proportionate to the weight of its coarser product either before or after it is discharged therefrom, are utilized to automatically regulate the feed for the constant operation of the machine to its full 105 capacity, maintains a uniform classifying action, and prevents undue strains on its operating parts.

We desire it understood that the system of devices shown in the drawings is merely 110 illustrative as one of many methods that may be employed to produce the desired results, and that our invention is applicable to any classifying machine irrespective of its size or construction.

Having thus described our invention what we claim and desire to secure by Letters-Patent is:

1. In combination, a classifier, an appliance for feeding material thereto, means for receiving the oversize product, and means for regulating the feeding action of said appliance by variations in the weight of an oversize product of the classifier.

2. In combination, a classifier, an appliance for feeding material thereto, means for receiving the oversize product, a valve-controlled liquid-supply, and mechanism for regulating the feeding action of said appliance by variations in the weight of an over- 125 130 135

size product of the classifier, including means to simultaneously regulate the liquid-supply by adjustment of its valve.

3. In an apparatus for the treatment of 5 granular material, a circuit, a feeding appliance, an electric motor for the feeding appliance, connected in the circuit, a rheostat in the circuit, and weighing means including a movable member for operating the rheostat 10 by variations in the weight of material under treatment to correspondingly regulate the feeding action of the appliance.

4. In an apparatus for the treatment of 15 granular material, a classifier, means for feeding material to said classifier, means for receiving the oversize from the classifier, a weigher for said oversize material and means for operating said feeding means including means for regulating the said supply actuated by the operation of said weigher.

5. In an apparatus for the treatment of 25 granular material, a classifier, weighing mechanism adapted to receive oversize from said classifier and having a lever supported element, a feeding appliance, a valve controlled liquid supply, and mechanism actuated through the medium of the lever by variations of material to regulate the feeding action of said appliance and to simultaneously regulate the liquid supply by the 30 adjustment of its valve.

6. In a classifying apparatus, a classifier, 35 weighing mechanism adapted to receive oversize from said classifier and having an element movable by variations in the weight of an oversize in material under treatment, a feeding appliance, and means actuated by movement of said element to correspondingly regulate the feeding action of said appliance.

7. In a classifying apparatus, a classifier, weighing mechanism adapted to receive oversize from said classifier and having an element movable by variations in the weight of an oversize in the material under treatment, a feeding appliance, a valve controlled liquid supply, and means actuated by movement of said element to regulate the feeding action of said appliance and other means also actuated by the said element for simultaneously regulating the liquid supply by 45 adjustment of its valve.

8. In classifying apparatus, a classifier, weighing mechanism having means connected therewith for receiving oversize material from said classifier, said weighing mechanism including an element movable by variations in weight of said oversize in material under treatment, a valve controlled liquid supply, and means actuated by movement of said element to correspondingly regulate the liquid supply by adjustment of its valve.

9. In an apparatus for the treatment of 65 granular material, a circuit, a feeding appliance, an electric motor for the feeding appliance connected in the circuit, and rheostat in the circuit, a valve controlled liquid supply, and weighing means including a movable member operated by variations in 70 the weight of material under treatment, and means connected with the said member and with the rheostat and the valve of the liquid supply for controlling the current and the supply of liquid.

In testimony whereof we have affixed our signatures.

ELMER R. RAMSEY.
ALFRED L. BLOMFIELD.
